METHOD OF MAKING AND FILLING TEA
BAGS, COFFEE BAGS, AND THE LIKEWilliam S. Patterson, Arlington, Mass., assignor
to Pneumatic Scale Corporation, Limited,
Quincy, Mass., a corporation of Massachusetts

Application May 8, 1940, Serial No. 333,895

3 Claims. (Cl. 93—3)

This invention relates to the manufacture of tea bags, coffee bags and the like and has for its general object to provide a novel method of making and filling tea bags according to which the bags are made from a web of bag material and are filled while the web occupies and is travelling in a vertical direction.

In carrying out my invention, a web of bag material is disposed in a vertical position and is then folded along a median line, and the two sides of the vertically extending folded web are united at spaced intervals to form pockets, each pocket being filled and subsequently sealed while the web is still in vertical position. Each filled pocket is subsequently severed from the web to form an individual filled tea bag.

One advantage resulting from this method is that a less complicated machine is required for making and filling the tea bags while the web is in the vertical position than is required when the bags are made and filled from a horizontally travelling web.

Another advantage is that a machine necessary to carry out my improved method requires less floor space than one in which the bags are made from a horizontally travelling web.

In order to give an understanding of the invention, I have illustrated in the drawing some selected embodiments thereof which will now be described after which the novel features will be pointed out in the appended claims.

In the drawing—

Figs. 1 and 2 are perspective more or less diagrammatic views illustrating the steps of my improved process.

Fig. 3 is a view of a tea bag made in accordance with my process.

Fig. 4 is a section on the line 4—4, Fig. 3.

Fig. 5 is a section on the line 5—5, Fig. 3.

Fig. 6 is a view similar to Fig. 1, but illustrating a slightly different embodiment of the invention.

Referring now to Figs. 1 and 2, 1 indicates a web of bag material from which the individual tea bags are made. This web is shown as passing over a guide roll 12 and as occupying a vertical position as it is delivered from the guide roll.

In accordance with my invention, the portion of the web which is delivered from the guide roll 12 and extends in a vertical direction is folded along a median line to present a vertically extending folded web having the two sides 2 and 3. These two sides are adhesively or otherwise united along successive separated zones 4 extending transversely to the web and as said two sides 55

2 and 3 are united along any transverse zone 4, the said sides will be simultaneously adhesively or otherwise united along a zone 5 adjacent the edges of the fold and which meets the zone 4, thereby to produce a pocket 6 between the folds which is bounded on one side by the fold 7 of the web, along another side by the zone 4 where the two sides are united, and along a third side by the zone 5 where the folds are also united at the edges.

The required amount of coffee, tea, or other material is then introduced into this pocket 6, after which the two sides 2 and 3 of the folded web are adhesively or otherwise united throughout another transverse zone 4, thereby to close and seal the open side of the pocket through which it is filled.

A succession of pockets are thus formed in the vertically extending portion of the web, and each pocket is formed, filled and sealed while it still constitutes an integral part of the web 1, as clearly seen from Fig. 2.

After each pocket has been filled and sealed, then it is severed from the web along a line bisecting the transverse zone 4, thereby to produce the filled tea bag 30 illustrated in Figs. 2, 3, 4 and 5.

It will be understood, of course, that any adhesive which is used for forming and sealing the pockets will be of such a character that it will not lose its adhesive properties when it is placed in hot water.

The web 1 of bag material may be made of any appropriate material. One material which is 35 well-adapted for this purpose is a porous fibrous material which contains a pressure-responsive binding material so that when two layers or plies of the material are pressed together, they will become and remain adhesively united.

If a bag material having these characteristics is used, then the pockets may be formed by clamping the folded web between two dies or clamping members, indicated at 8 and 9. Each of these clamping members is illustrated as having an L shape and as being provided with a horizontal leg 10 which extends transversely of the web and a vertical leg 11 which extends longitudinally of the web adjacent the edges thereof.

The web 1 in Fig. 1 is shown as passing over 50 a guide roll 12 and then through a folding element 13 by which it is folded longitudinally to form the two sides 2, and 3. The folded web material then passes between the clamping members 8 and 9 which press the two sides of the web together. If the web is a porous web carry-

ing a pressure-responsive binder, then the pressure which the dies 8 and 9 apply to the folded web will cause the two sides 2 and 3 to be adhesively united along the transverse zone 4 and the longitudinal zone 5. The pressure developed by the arms 18 of the dies or clamping members adhesively unite the two folds of the web along the transverse zone 4, and the arms 5 of the clamping members adhesively unite the two sides of the fold along the zone 5.

The action of the clamping members 8 and 9 in adhesively uniting the two sides 2 and 3 of the web along the zones 4 and 5 forms a pocket 6 between the sides of the fold which is closed on one side by the folded edge 7, on the bottom side by the zone 4 throughout which the two sides of the web are adhesively united and on another side by the zone 5 throughout which the sides 2 and 3 are also adhesively united, said pocket being open at its top side. This pocket can be filled through its open top side in any appropriate way, as by means of a delivery tube or spout 14, the delivery end of which lies between the sides 2 and 3 of the partially folded web. Said spout leads to any suitable hopper or other means for delivering measured quantities of tea, coffee and the like.

When any pocket 6 has been thus formed and filled, then the web is advanced one step which carries the filled pocket below the clamping devices 8 and 9 and into the position of the pocket indicated at 6a, it being understood that said clamping devices will be actuated to release the pressure on the web when the latter is to be moved forward. After the web has been advanced, said clamping devices are then again actuated to adhesively unite the web along other zones 4 and 5 during which operation the cementing together of the sides 2 and 3 of the fold along the zone 4 serves to seal the pocket 6 which has just been filled. The sealing of a filled pocket is thus accomplished simultaneously with the forming of the next successive pocket. When the second pocket has been formed, then it is filled, as above described, and the web again advanced one step into position for the formation of a third pocket.

The operation of adhesively uniting the sides 2 and 3 of the web to form the third pocket serves simultaneously to seal the second pocket which has previously been filled.

After each pocket has been filled and sealed, then it is severed from the web, thereby to form a tea bag 30 having the folded edge 7 and having the other three sides 15, 16, 17, adhesively united.

This severing of each individually filled and sealed pocket from the web may be accomplished by any suitable means such as a shearing device comprising a ledger blade 18 and a pivoted cutting member 19.

The web may be fed forward in any appropriate way, and by means of feeding rolls indicated at 20 and 21.

Another way of forming the pockets is indicated in Fig. 6 wherein the web 1a of bag material is provided on one side with spaced transverse bands 4a of adhesive material, which bands extend transversely of the web, and also is provided with bands 5a extending along the edges of the web. This adhesive material may be applied to a web of fabric or any other material in any suitable way. This web 1a is folded longitudinally as above described, and then passes between the clamping members 8a and 9a which operate to press the sides 2a, 3a of web material

together along the zones where the adhesive material has been applied, thereby to form the pockets. These pockets are filled, as above described, and then they are sealed and are afterwards severed from the bag material.

One way of applying the bands 4a, 5a of adhesive to one face of the web material 1a would be by passing the web between two rolls 22, 23, the roller 22 being an adhesive applying roller which is formed so that at each rotation thereof, it will apply a band 4a of adhesive to the face of the fabric, said roller being constructed to apply to the face of the fabric the continuous bands 5a at the edges of the fabric.

I have referred above to the use of a pressure-responsive adhesive for cementing together or adhesively uniting the two sides 2 and 3 of the folded web, but the invention is not limited to the use of any particular type of adhesive for this purpose. A thermo-plastic adhesive which requires the application of heat to soften it and cause it to adhere may be used, and if this type of adhesive is employed, then the clamping members 8 and 9 may be provided with means to heat them so as to furnish the necessary heat to soften the thermo-plastic adhesive.

Any other suitable form of adhesive may be used, however, without in any way departing from the invention, and, as stated above, if heat is necessary to soften or dry the adhesive, then provision may be made for heating the clamping members 8 and 9.

If desired, the adhesively united edges of each tea bag may be embossed or imprinted or otherwise marked to indicate the character of the material within the bag, the brand name, or any other data regarding the tea bag.

One way in which this could be done would be to make the clamping members 8 and 9 of such a character that they would function as embossing dies as well as clamping means for applying the necessary pressure to the folded sides of the web to secure the adhesive union between said sides. Or said clamping members 8 and 9 might be constructed so that they would make an imprint on the adhesively united edges of each pocket.

Another way of providing each tea bag with suitable markings would be to construct the clamping members 8 and 9 so that they would perforate the adhesively united edges of each tea bag at the time pressure was applied thereto.

In all the embodiments of my invention, it is to be noted that the web is disposed in a substantially vertical position when it is folded and while the pockets are being formed therein and are being filled and sealed, and I regard this as of some importance partly because a simpler machine occupying less floor space will be required to form the tea bags in this way than is required where the web is travelling in a horizontal direction as the tea bags are being formed and filled.

I claim:

1. The method of making and filling tea bags and the like which comprises folding a web of bag material along a line extending longitudinally thereof, adhesively uniting the two sides of the folded web throughout two zones simultaneously, one zone extending transversely of the web and the other zone extending longitudinally of the web adjacent the edges thereof, thereby to form a pocket closed on one side by the fold of the web and on two other sides by the adhesively united portions of the web, filling said

ocket with infusion-producing material, adhesively uniting the two sides of the fold throughout a second zone extending transversely of the web, thereby to seal said pocket and then severing said sealed pocket from the web.

2. The method of making and filling tea bags and the like which comprises folding a web of bag material along a median line extending longitudinally thereof, adhesively uniting the two sides of the folded web throughout a zone extending transversely of the web and simultaneously adhesively uniting said sides throughout another zone extending longitudinally of the web adjacent the edges thereof, thereby to form a pocket which is closed on one side by the fold of the web and on two other sides by the adhesively united portions of the web, filling said pocket with infusion-producing material, adhesively uniting said web throughout a second zone extending transversely of the web and also 20 throughout a second zone extending longitudinally of the web adjacent the edges thereof which second longitudinal zone connects with the first-named longitudinally extending zone, thereby to seal the filled pocket and to form a second pocket, filling said second pocket with infusion-producing material and then repeating said operations to form and fill other pockets.

3. The method of making and filling tea bags and the like which comprises folding a web of bag material progressively along a median line extending longitudinally of the web, adhesively uniting the two sides of the folded web throughout two zones simultaneously, one zone extending transversely of the web and the other zone extending longitudinally of the web adjacent the edges thereof, thereby to form a pocket closed 5 on one side by the fold of the web and on two other sides by the adhesively united portions of the web, filling said pocket with infusion-producing material, adhesively uniting the two sides of the folded web throughout a second zone extending transversely of the web and simultaneously adhesively uniting said sides throughout another zone extending longitudinally of the web adjacent the edges thereof to seal the filled pocket and to form an additional unfilled pocket, 10 filling the additional pocket with infusion-producing material, repeating the above operations of sealing each pocket as it is formed and forming and filling an additional pocket, and severing each filled pocket from the web after it has been sealed.
